UNITED STATES PATENT OFFICE.

BERNARD BENEDICT, OF NEW YORK, N. Y., ASSIGNOR TO BEACON MINIATURE ELECTRIC CO., INC., OF NEW YORK, N. Y., A CORPORATION OF NEW YORK.

FLASH-LIGHT.

1,182,965.

Specification of Letters Patent. Patented May 16, 1916.

Application filed December 30, 1914. Serial No. 879,632.

To all whom it may concern:

Be it known that I, BERNARD BENEDICT, a citizen of the United States, and a resident of Bronx, in the county of Bronx and State of New York, have invented certain new and useful Improvements in Flash-Lights, of which the following is a specification.

The invention pertains more particularly to flash lights adapted to be carried in the upper vest pocket without inconvenience and in the same manner that a fountain pen is carried.

The flash light of my invention is provided with a spring clip or member adapted, when the flash light is placed in the upper vest pocket, to embrace between itself and the side of the casing of the article, the thickness of the material of the vest at the outer side of said pocket, the flash light being thereby held securely.

The present invention resides more particularly in the structure of the casing and in the electric circuit features. In the present instance a manually operative contact is rigid with the exterior casing and has a portion to be pressed inwardly through said casing for engaging a conductor connected with the battery, thereby to complete the circuit, and this conductor is preferably in the form of a sleeve closely fitting within but insulated from the exterior casing and in electrical engagement with a spring, which engages one end of the battery and is insulated from the exterior casing. The casing of my invention is composed of two main parts secured together by bayonet joints.

In carrying out my invention I preferably construct the barrel or exterior casing of the flash light to resemble in appearance a fountain pen, and upon the exterior of this outer shell or casing I secure a spring clip, preferably imitating as far as possible the spring clip on the side of the barrel of a fountain pen, and I preferably utilize this spring clip as the manually operative means for closing the circuit when it is desired that the lamp shall light. I do not limit my invention however to the use of the spring clip as a circuit closer,

since it is obvious that other forms of circuit closers may be used either in connection with or separate from the spring clip.

The invention will be fully understood from the detailed description hereinafter presented, reference being had to the accompanying drawings, in which:

Figure 1 is a front elevation of a flash light embodying my invention. Fig. 2 is a central vertical section on an enlarged scale through the same, taken on the dotted line 2—2 of Fig. 1; Fig. 3 is a detached perspective view of an inner non-conducting lining for the interior of the handle end of the flash light, said lining having a small aperture in one side thereof for the passage of the circuit closer; Fig. 4 is a detached perspective view of a metal sleeve which in use fits within the lining shown in Fig. 3 when said lining is within the exterior shell or casing of the flash light; Fig. 5 is a sectional view through the metal portion of the flash light taken at right angles to the section of Fig. 2 and is presented to illustrate the bayonet locks for connecting the two main sections of the exterior casing together; Fig. 6 is a detached side elevation of the inner end portion of the outer section of the main casing; Fig. 7 is a top view of the same, and Fig. 8 is a horizontal section through the flash light taken on the dotted line 8—8 of Fig. 2.

In the drawings, 10 designates the exterior shell or casing of the flash light, and this shell or casing is of elongated form and meant to imitate as far as convenient the appearance of a fountain pen. The casing 10 will preferably be of metal and at one end carries a lamp 11 and reflector 12 therefor. The casing 10 is shown as made in two sections 13, 14 connected together at their meeting portions by bayonet joints. The section 13 near its inner end flares outwardly, as at 15, and at the outer edge of this flaring portion 15 said casing section is formed with an inwardly set straight portion 16, this construction creating an annular shoulder 17 at the adjoining edges of said portions 15, 16, as clearly illustrated in Figs. 5, 6 and 7. The portion 16 of the casing section 13 is in the nature of a band and

has pressed in its opposite sides the grooves 18 for the bayonet locks, these grooves having at the inner ends of their transverse portions outwardly projecting recesses 19 which serve to aid in locking the two sections of the main casing against accidental rotation one upon the other, tending to separate them. The casing section 14 is plain and cylindrical from end to end and snugly 10 receives within its inner end the band 16 of the casing section 13, the edge of the inner end of the section 14 abutting against the shoulder 17 of the casing section 13, this construction and arrangement affording a 15 firm connection between the two casing sections and creating a neat joint at their meeting portions. The inner end of the casing section 14 is indented, as at 20, to form two small studs opposite to each other to 20 enter the opposite grooves 18 of the bayonet locks.

In assembling the casing sections 13, 14, the band 16 of the section 13 is inserted within the inner end of the section 14 in 25 position for the studs at 20 to enter the open ends of the grooves 18 and thereupon said band 16 having been fully inserted within the casing section 14, the section 13 is given a rotary movement to carry the horizontal 30 portions of the grooves 18 along the studs 20, said studs upon reaching the inner ends of the said horizontal portions of the grooves 18 getting into line with the recesses 19, and thereupon under the pressure of the 35 conducting spring 21, the sections 13, 14 are moved very slightly in a direction from each other and the said studs enter the recesses 19 to a sufficient extent to lock the sections 13, 14 against accidental rotation one upon 40 the other. The outer end of the casing section 13 is formed at 22 with bayonet lock grooves, and the opposite sides of the reflector shell 12 are indented, at 23, to form studs to engage said grooves, the grooves 22 45 and studs 23 corresponding exactly with the grooves 18 and studs 20 provided at the adjoining ends of the casing sections 13, 14, and therefore not requiring further specific description, the dotted lines at the lower 50 portion of Fig. 2 sufficiently illustrating the grooves 22 and studs 23. The reflector 12 is therefore held within the outer end of the casing section 13 by bayonet locks, and said reflector at its outer edge is formed with a 55 shoulder 24 to engage the outer edge of the casing section 13. The reflector 12 has a threaded neck 25 to receive the socket 26 of the lamp in a customary manner. The lamp 11 is of usual character and has one 60 terminal 27 in engagement, as usual, with one pole of the battery 28. The battery 28 will customarily be formed of two cells in end to end relation and covered around their sides by paper or other non-conducting ma-

terial, in the customary manner. The paper 65 covering the cells of the battery 28 insulate the sides of the battery from the exterior casing and also from the inner conducting sleeve 30 hereinafter described.

The casing section 14 is somewhat greater 70 in diameter than the section 13, and said section 14 is lined by a sleeve 29 of non-conducting material, such as paper, and within the non-conducting sleeve 29 is a metal sleeve 30. The battery 28 has one end portion within the sleeve 30 and said portion of the battery at its end is pressed against by the coiled spring 21 which is a conductor and has one or more of its coils in electrical engagement with the sleeve 30. 80 The sleeve 30 is insulated from the metal casing section 14 by means of the sleeve 29 and also by means of a disk of paper or the like 31 fitted within the closed end of the section 14. Within the outer end of the sleeve 30 is placed a second disk, which I number 32, of paper or the like, the disk 32 being in face to face contact with the disk 31 and receiving the outer end of the spring 21. The sleeves 29, 30 are in the form of elongated split tubes and therefore may be readily applied to position with the outer or handle portion of the casing or casing-section 14. The disk 31 binds tightly within and against the outer end of the insulating sleeve 29 and aids in securing said sleeve in position. The disk 32 binds tightly within and against the outer end of the conducting sleeve 30 and aids in securing said sleeve in position. It will be seen that the disks 31, 32 and sleeve 29 insulate the conducting sleeve 30 and spring 21 from the casing section 14 and that the circuit from the outer end of the battery 28 will be from the battery to the spring 21 and thence to the sleeve 30. The sleeve 29 is formed near its forward end with an aperture or hole 33, and this aperture 33 is in line with a corresponding aperture 34 formed in the casing section 14 and exposes at said aperture 34 a 100 small portion of the conducting sleeve 30. The electrical connection of the outer casing of the flash light with the sleeve 30 to complete the circuit is made at the openings 33, 34, and in the present instance I utilize a spring clip 35 as the circuit closer, said clip being secured by rivets to the casing section 14 or otherwise suitably connected with said casing so as to be in electrical engagement or connection therewith. On the 105 outer end of the spring clip 35 is a ball or enlargement 36 adapted by the pressure of the thumb applied thereon to be moved, on the flexing of the spring 35, inwardly through the openings 34, 33, against the sleeve 30, thereby to complete the circuit from the battery to the spring 21 and through the sleeve 30 to the spring clip or 110 115 120 125

circuit closer 35 and thence to the casing section 14 which is in electrical engagement with the casing section 13, reflector 12 and one terminal of the lamp, whose other terminal 27 is in electrical engagement with the forward end of the battery, as usual.

One of the more desirable features of my invention resides in the use of the sleeve 30 and spring 21, both insulated from the casing section 14, but in electrical engagement with each other. This sleeve 30 permits me to have the exterior side surface of the battery 28 completely covered by paper or other insulating material, and latter permits the use within the flash light of batteries as marketed without manipulating them further than to insert them within the flash light casing. Since the sleeve 30 when placed within the casing is in electrical connection with the battery and is similar in cross-section, it may be applied within the casing section 14 without regard to the location of the opening 33 in the sleeve 20, any portion of the sleeve 30 serving to cooperate with the circuit closer to complete the circuit.

The spring 21 acts by pressing against the battery 28 to force the lamp 11 and reflector 12 forwardly and thereby to interlock the projections 29 on the reflector with the grooves 22 on the casing section 13 and at the same time to press the casing section 13 forwardly so that the recesses 19 of the grooves 18 may be carried into interlocking engagement with the indentations or studs 20 of the casing section 14.

I prefer to utilize the part 30 both as a spring clip and as a circuit closer, and hence I have given to it the shape and proportions shown, but if it were desired to use said part only as a circuit closer it would naturally be made shorter and constitute simply a resilient tongue or arm having at its free end a part to be pressed against the conductor 30; and under this condition a separate spring clip, as commonly used on pens and pencils, might appropriately be applied to the casing section 14 as an aid to securing the flash light in the pocket of the owner. It is obvious that the circuit-closer arm may be variously constructed within the scope and spirit of my invention.

What I claim as my invention and desire to secure by Letters-Patent is:

1. A portable electric light comprising an exterior casing consisting of a plurality of detachably connected sections, a lamp having a lamp at the outer end of its forward section and a spring in the interior of its rear section, a plural cell battery within said casing electrically connected with said lamp, a non-conducting lining within the rear section of said casing, a conductor at the inner side of said lining electrically connected with

rear cell of said battery and exposed at the side opening in said rear casing section, said conductor being insulated by the wrapping on the battery from the side thereof, and a circuit closer in electrical connection with said casing and located at said side opening 70 thereon to be engaged with said conductor for completing the circuit.

2. A portable electric light comprising an exterior casing consisting of a plurality of detachably connected sections and having a lamp at the outer end of its forward section and an opening in the side of its rear section, a plural cell battery within said casing electrically connected with said lamp, a non-conducting lining within the rear section of said casing, a conductor at the inner side of said lining electrically connected with the rear cell of said battery and exposed at the side opening in said rear casing section, said conductor being insulated by the wrapping 85 on the battery from the side thereof, and a resilient arm in electrical connection with said casing and at its free end having a part to be engaged at said side opening with said conductor for completing the circuit. 90

3. A portable electric light comprising an exterior casing consisting of a plurality of detachably connected sections and having a lamp at the outer end of its forward section and an opening in the side of its rear section, a plural cell battery within said casing electrically connected with said lamp, a non-conducting lining within the rear section of said casing, a conductor at the inner side of said lining electrically connected with the rear cell of said battery and exposed at the side opening in said rear casing section, said conductor being insulated by the wrapping on the battery from the side thereof, and a resilient arm in electrical connection 105 with said casing and at its free end having a part to be engaged at said side opening with said conductor for completing the circuit, said resilient arm being elongated and adapted to serve as a clip for securing the device in the pocket. 110

4. A portable electric light comprising an exterior casing consisting of a plurality of detachably connected sections and having a lamp at the outer end of its forward section 115 and an opening in the side of its rear section, a plural cell battery within said casing electrically connected with said lamp, a non-conducting lining within the rear section of said casing, a conductor at the inner side 120 of said lining electrically connected with the rear cell of said battery and exposed at the side opening in said rear casing section, said conductor being insulated by the wrapping on the battery from the side thereof, 125 and a circuit closer in electrical connection with said casing and located at said side opening therein to be engaged with said

conductor for completing the circuit, said lining being tubular and fitting the inner walls of the rear casing section and having an opening in its side registering with the aforesaid opening in the side of said casing, and said conductor being a sleeve fitting within said lining.

5. A portable electric light comprising an exterior casing consisting of a plurality of 10 detachably connected sections and having a lamp at the outer end of its forward section and an opening in the side of its rear section, a plural cell battery within said casing electrically connected with said lamp, a non-conducting lining-sleeve fitting within the 15 rear section of said casing, a non-conducting disk lining the rear end of said casing, a conducting sleeve fitted within said lining-sleeve and exposed at said side opening in 20 said casing, a conducting spring in the outer end of the rear casing section in electrical connection with said battery and said conducting sleeve, and a circuit closer in electrical connection with said casing and located at said side opening to be pressed 25 against said conducting sleeve for completing the circuit.

6. A portable electric light comprising an exterior casing consisting of a plurality of 30 detachably connected sections and having a lamp at the outer end of its forward section and an opening in the side of its rear section, a plural cell battery within said casing electrically connected with said lamp, a non-conducting lining-sleeve fitting within the 35 rear section of said casing, a disk fitting within the rear end of said lining-sleeve and binding the same against said casing, a conducting sleeve fitting within said lining-sleeve and exposed at said side opening in 40 said casing, a non-conducting disk fitting within the rear end of said conducting sleeve and binding the same against said lining-sleeve, a conducting spring within 45 and binding against the outer or rear end of said conducting sleeve and in electrical connection with said battery, and a resilient circuit closer in electrical connection with said casing and located at said side opening 50 and having a part to be pressed inwardly against said conducting sleeve for completing the circuit.

7. A portable electric light comprising an exterior casing consisting of a plurality of 55 detachably connected sections and having a lamp at the outer end of its forward section and an opening in the side of its rear section, a plural cell battery within said casing electrically connected with said lamp, a non-conducting lining-sleeve fitting within 60 the rear section of said casing, a non-conducting disk lining the rear end of said casing, a conducting sleeve fitted within said lining-sleeve and exposed at said side open-

ing in said casing, a conducting spring in the outer end of the rear casing section in electrical connection with said battery and said conducting sleeve, and a circuit closer in electrical connection with said casing and located at said side opening to be pressed 70 against said conducting sleeve for completing the circuit, said circuit closer being a resilient conducting arm connected with the side of said casing and adapted to serve as a clip for securing the device in the pocket. 75

8. A portable electric light comprising an exterior metal casing, a battery within said casing, a lamp at the forward end of said casing electrically connected therewith and with the forward end of said battery, a non-conducting split tube lining-sleeve fitting within the other end portion of said casing, a disk fitting within the rear end of said casing and insulating, with said lining sleeve, the battery from said casing, a split 85 tube conductor fitting within said non-conducting lining-sleeve, a conducting spring engaging the rear end of said battery and said conducting sleeve and confined within said sleeve, and a circuit closer to be engaged 90 with said conductor for completing the circuit.

9. A portable electric light comprising an exterior metal casing, a battery within said casing, a lamp at the forward end of said 95 casing electrically connected therewith and with the forward end of said battery, a non-conducting split tube lining-sleeve fitting within the other end portion of said casing, a disk fitting within the rear end of said 100 casing and insulating, with said lining sleeve, the battery from said casing, a split tube conductor fitting within said non-conducting lining-sleeve, a conducting spring engaging the rear end of said battery and said conducting sleeve and confined within 105 said sleeve, and a circuit closer to be engaged with said conductor for completing the circuit, said casing and said non-conducting lining sleeve having registering 110 openings therein at said circuit closer and thereby exposing a portion of said conductor to be engaged by said circuit closer.

10. A portable electric light comprising a metal casing, a lamp at one end thereof 115 and in electrical connection therewith, a battery within said casing in electrical engagement with said lamp, a non-conducting lining within said casing, a conductor between the battery and said lining and insulated from the side of the battery, a spring in the rear end of said casing and normally insulated therefrom and engaging the adjacent end of said battery and also said conductor, and a circuit closer in electrical connection with said casing and adapted for 120 manual operation, said casing having an opening in the side thereof at said circuit 125

closer, and said lining exposing a portion of
said conductor in line with said opening,
and said circuit closer being adapted to be
engaged through the opening in the casing
with said conductor for completing the cir-
cuit.

Signed at New York city, in the county

of New York, and State of New York, this
28th day of December, A. D. 1914.
